UNITED STATES PATENT OFFICE.

SETH ALBERT PLOUGH, OF TRAVERSE CITY, MICHIGAN.

VALVE.

No. 831,018.

Specification of Letters Patent.

Patented Sept. 11, 1906.

Application filed June 10, 1905. Serial No. 264,608.

To all whom it may concern:

Be it known that I, SETH ALBERT PLOUGH, a citizen of the United States, and a resident of Traverse City, in the county of Grand 5 Traverse and State of Michigan, have invented a new and Improved Valve, of which the following is a full, clear, and exact description.

The object of the invention is to provide a 10 new and improved valve arranged to shut off the flow of fluid through the valve by the use of an emergency-valve whenever the main plug breaks or becomes out of order and to allow of conveniently removing the broken 15 main plug for repairs or for replacing it by a new one and to permit resetting of the emergency-valve after the repairs are made to again allow the use of the valve for its legitimate purpose.

20 The invention consists of novel features and parts and combinations of the same, which will be more fully described herein-after and pointed out in the claims.

A practical embodiment of the invention 25 is represented in the accompanying drawings, forming a part of this specification, in which similar characters of reference indicate corresponding parts in all the views.

Figure 1 is a longitudinal central section of 30 the improvement. Fig. 2 is an end view of the same, parts being broken out. Fig. 3 is a perspective view of the emergency-valve. Fig. 4 is a like view of the gate-valve. Fig. 5 is a like view of the seat for the gate-valve; 35 and Fig. 6 is a reduced longitudinal central section of the improvement, showing the emergency-valve controlling the flow of the fluid.

The body A of the valve is provided with 40 the usual inlet A' and the outlet A², both extending from a conical valve-seat A³, in which is mounted to turn an emergency-valve B, having oppositely-disposed openings B' and B², adapted to register with the inlet A' and the outlet A² or to be moved out 45 of register with the same. Normally the emergency-valve B is in an active position—that is, its openings B' and B² register with the inlet and outlet A' and A², respectively. 50 The emergency-valve B is locked in either of its two positions by a set-screw C, screwing in the body A against the emergency-valve B, as plainly indicated in Fig. 2.

The lower end of the emergency-valve B is 55 provided with a threaded portion B³, on which screws a nut D against a washer E,

resting on the under side of the body A. Thus by screwing up the nut D the emergency-valve B can be properly drawn into position in its conical valve-seat A³. The 60 lower terminal B⁴ of the emergency-valve B is preferably made polygonal to allow convenient application of a wrench or similar tool (see Fig. 6) to permit the operator to turn the emergency-valve B from an active 65 or open position, such as shown in Figs. 1 and 2, into an inactive or closed position—that is, to move the openings B' and B² out of register with the inlet A' and the outlet A² to shut off the flow of the fluid through 70 the valve.

Previous to turning the emergency-valve B, as described, it is necessary to partly unscrew the set-screw C, and after the emergency-valve B has been turned to the desired position the set-screw C is screwed up to securely hold the emergency-valve against turning.

On the upper end of the emergency-valve B screws a cap F and on the lower end of the body A screws a cap F', adapted to be interchanged with the cap F for the purpose hereinafter more fully described. Within the said emergency-valve is fitted a main valve-plug G, having forked members G' G², provided with openings G³ G⁴, adapted to register with the openings B' and B² in the emergency-valve B. The forked members G' and G² are adapted to be engaged by the tapering or split end H' of a gate-valve H, contained within the emergency-valve B, and in the 90 said gate-valve H screws the threaded end I' of a stem I, extending loosely through the cap F and provided at its outer end with a suitable handle I² for turning the stem, so as to cause the threaded portion I' to move the 95 gate-valve H up or down in the emergency-valve B, according to the direction in which the said handle I² is turned. On the stem I is arranged a collar I³, seated in a seat B⁵, formed on the upper end of the emergency-valve B, and the said collar I³ is held in place on the said seat by the cap F. By screwing the handle I² in one direction the gate-valve H is moved downward, so as to engage its end H' with the forked members G' and G² of the valve-plug G and close the openings G³ and G⁴ to shut off the flow of the fluid through 100 the valve. When it is desired to open the valve, the handle I² is turned in the opposite direction, so as to lift the gate-valve H and the end H' thereof to uncover the openings G³ and G⁴, thereby again allowing the pas-

sage of the fluid through the valve. In order to insure a firm seating of the members of the split end H' on the forked members G' G², the terminals of the split members engage a 5 wedge-shaped projection G⁵ on the plug G, as will be readily understood by reference to Fig. 1.

In case the main valve-plug G or the gate-valve H and parts connected therewith break or become out of order and it is desired to repair the same then the operator unscrews the cap F' and the set-screw C and applies a wrench or other tool on the polygonal portion B⁴ to give a quarter-turn to the emergency-valve B, thus closing the emergency-valve by moving the openings B' and B² out of register with the inlet A' and the outlet A². When this has been done, the set-screw C' is screwed up to again lock the emergency-valve B in place. The operator now unscrews the cap F and pulls out the gate-valve H and the plug G to repair the same or to replace the parts by new ones. In order to permit the use of the valve during the time the repairs 20 are made, the cap F' is screwed in position on the top of the emergency-valve B to close the upper end thereof (see Fig. 6) to allow of turning the emergency-valve B back into an open position to permit fluid to flow through the 25 valve, although the gate-valve H and the plug G are removed for repairs. After the repairs are made the emergency-valve is again turned into a closed position, the cap F' is removed, and then the repaired or renewed 30 parts H and G are placed back into proper position in the emergency-valve B. The operator now replaces the cap F, unscrews the set-screw C, and then turns the emergency-valve B back to its normal active or open position—that is, to bring the openings B' and 35 B² again in register with the inlet A' and the outlet A². When this has been done, the operator replaces the cap F' and screws up the set-screw C to securely hold the emergency-valve B locked in an active position to permit the proper flow of the fluid through the 40 valve whenever the gate-valve H is moved into an open position.

Having thus described my invention, I 45 claim as new and desire to secure by Letters Patent—

1. A valve comprising a valve-body having a valve-seat, an inlet and outlet connected with the said valve-seat, an emergency-valve mounted to turn on the said valve-seat and adapted to be moved in or out of register with the said inlet and the said outlet, the said emergency-valve being open at one end 50 for the reception or removal of the regular valve, and a cap for closing the said open end of the emergency-valve during the time the regular valve is removed.

2. A valve comprising a valve-body having a valve-seat and an inlet and outlet connected with the said valve-seat, an emergency-valve mounted to turn on the said valve-seat and provided with openings adapted to be moved in and out of register with the said inlet and the said outlet, a valve-plug in the emergency-valve, and provided with 55 openings adapted to register with the openings in said emergency-valve, and a gate-valve for controlling the openings in the said valve-plug.

3. A valve comprising a valve-body having a valve-seat and an inlet and outlet connected with the said valve-seat, an emergency-valve mounted to turn on the said valve-seat and adapted to be moved in and out of register with the said inlet and the said outlet, means for locking the said emergency-valve in open or closed position, a valve in the said emergency-valve and provided with a valve-plug, a gate-valve for engaging the said valve-plug, and means for moving the 85 said gate-valve into an open or closed position relative to the said valve-plug.

4. A valve comprising a valve-body having a valve-seat and an inlet and outlet connected with the said valve-seat, an emergency-valve mounted to turn on the said valve-seat and adapted to be moved in and out of register with the said inlet and the said outlet, means for locking the said emergency-valve in an open or closed position, a valve in 90 the said emergency-valve and provided with a valve-plug, a gate-valve for engaging the said valve-plug, a stem screwing on the said gate-valve and provided with a collar seated on the said emergency-valve, and a cap on 95 the said emergency-valve for holding the said collar on its seat.

5. The combination with a valve-body having a valve-seat and provided with an inlet and an outlet, of an emergency-valve mounted to turn on the said valve-seat and provided with openings adapted to be moved in and out of register with the said inlet and the said outlet, a valve-plug fitted within the said emergency-valve and having forked members 105 provided with openings adapted to register with the openings in the emergency-valve, a gate-valve having its end shaped to fit between the forked members of the valve-plug, and means for moving the gate-valve 110 to close or uncover the openings in said forked members.

In testimony whereof I have signed my name to this specification in the presence of two subscribing witnesses.

SETH ALBERT PLOUGH.
